COMBINED TELEPHONE HANDSET AND DESK STAND

Henry Dreyfuss, South Pasadena, Calif., assignor to Bell
Telephone Laboratories, Incorporated, Murray Hill,
Berkeley Heights, N.J., a corporation of New York

Filed July 3, 1967, Ser. No. 7,682

Term of patent 14 years

(Cl. D26—14)

FIG. 1

FIG. 1 is a perspective view of a combined telephone handset and desk stand showing my new design;

FIG. 2 is an end elevation taken at a reduced scale with the cover member in a closed position. The view is partially broken away and in cross section for clarity of illustration;

FIG. 3 is a plan view as seen from the top of FIG. 1 with the handset removed for ease of illustration;

FIG. 4 is an end elevation partially broken away and in cross-section with the handset in its normal position; and

FIG. 5 is a rear elevation with the cover in a closed position.

The dominant features of my new design reside in the portions shown in full lines on the drawing.

I claim:

The ornamental design for a combined telephone handset and desk stand, substantially as shown and described.
